Alfred Berney

United States Patent Office.

ALFRED BERNEY, OF JERSEY CITY, NEW JERSEY.

Design No. 3,232, dated November 10, 1868.

DESIGN FOR A TRADE-MARK

The Schedule referred to in these Letters Patent and making part of the same.

To all whom it may concern:

Be it known that I, ALFRED BERNEY, of Jersey City, in the county of Hudson, and State of New Jersey, have originated and produced a new Design for a Trade-Mark, applicable to tea-kettle boilers and other culinary utensils, of which the following is a full, clear, and exact description, reference being had to the accompanying drawing, making part of this specification, and which represents my new design for a trade-mark as applied to a tea-kettle boiler.

In the accompanying drawing, the trade-mark, as shown at A, is of circular character, with the words around the design, in the centre, "A. Berney's Trade-Mark, New York, Patented," and on the design, in the centre, the words "Use the Tea-Kettle Boiler." Said

design, in the centre, consists of an ordinary tea-kettle, B, with its lid *a* on one side, detached, the kettle A having a boiler, C, of taper form, seated within it, and provided with a lid, spout, and handle, mounted by a fanciful device, representing a cow's udder, *b*, crossed by ears of corn, *c c*, and a sheaf of wheat, *d*.

What I claim as my invention, and desire to secure by Letters Patent, is—

The design for a trade-mark, as herein shown, and embraced within the circle A, as described.

ALFRED BERNEY.
